UNITED STATES PATENT OFFICE.

HARVEY HUBBELL, OF BRIDGEPORT, CONNECTICUT.

DESIGN FOR AN ELECTRIC-WIRE FASTENING.

SPECIFICATION forming part of Design No. 23,322, dated May 29, 1894.

Aplication filed April 3, 1894. Serial No. 506,224. Term of patent 7 years.

To all whom it may concern:

Be it known that I, HARVEY HUBBELL, a citizen of the United States, and a resident of Bridgeport, Fairfield county, Connecticut, have invented a Design for an Electric-Wire Fastening, of which the following is a specification.

My design for a fastener for electric wiring is illustrated in the accompanying drawing and comprises a body A, with two jaw-shaped legs B and B', and with a clear space C between the legs, which have the inclined notches b b'. The body A has openings a a,

but the characteristic features of my design are the jaw-shaped legs with the space C between them.

I claim as my invention—

The design for a fastener, substantially as herein shown and described.

In testimony whereof I have signed my name to this specification in the presence of two subscribing witnesses.

HARVEY HUBBELL.
